UNITED STATES PATENT OFFICE

2,497,363

LAST FOR SHOES

James Edwin Mackay, Street, England, assignor
to C. & J. Clark Limited, Street, Somerset, Eng-
land, a British company

Application November 15, 1948, Serial No. 59,999
In Great Britain October 22, 1948

4 Claims. (Cl. 12—136)

1

The present invention relates to improvements in lasts used in the manufacture of boots and shoes, hereinafter referred to collectively as shoes, and also to trees used for the purpose of maintaining the form of a shoe when it is out of use, the expression "last" being used in this specification to include a tree.

It is known in the manufacture of shoes to use a last which is constructed in at least two relatively movable parts in order that the wide heel part may be displaced toward the front of the last so as to pass easily into and out of the opening in the shoe upper above the waist of the shoe. The reason for this is that the rear portion of a shoe narrows inwardly in an upward direction away from the heel in order to fit snugly about the foot of the wearer in the region of the ankle but by causing the parts of a last to move relatively as described above the insertion and removal of the last can be effected without distorting or stretching the edge of the opening in the shoe upper.

In the specification of my prior United States Patent No. 2,426,516 there is described a three-part last which broadly comprises a front portion and a two-part rear portion consisting of an upper rear part linked to and rockable on the front portion and a lower rear part pivotally connected to said upper rear part by a link means which permits the lower rear part to swing toward the front portion as said upper rear part is rocked toward said front portion. In the particular embodiments of the prior invention which are described in the patent specification referred to, separate upper and lower parts, which together constituted the rear portion of the last, had between them a plane of cleavage extending from the back of the last through to a position below the axis about which a one-piece front portion rocked in relation to the two-part rear portion. The link means between the two parts of the rear portion was such that as the upper part of the rear portion, which conformed generally to the ankle of the foot of the intended wearer, was made to perform a hinged movement in relation to the one-piece front portion, the lower rear part, corresponding in shape to the heel of the foot on which the shoe was intended to be worn, was free to swing upon its connecting link toward and away from the front portion of the last. It is stated in the patent specification referred to that a spring could be provided to force the lower part of the rear portion forwardly when the rear portion is hinged relatively to the front portion. The prior patent specification accordingly provides one means for effecting the automatic forward displacement of the heel part of the last, which is a feature of particular value when removing the last from a shoe.

It is an object of the present invention to provide an improved three-part last of the same

2

general character as that described in the specification of my prior United States patent specification No. 2,426,516.

Another object of the present invention is to provide a three-part last of the character referred to, which employs improved means for effecting the automatic forward displacement of the heel part of the last, that is, for effecting automatic "shortening" of the last as a whole during the act of insertion or of removal thereof.

A further object of the present invention is to provide a three-part last comprising a front portion and a two-part rear portion consisting of an upper rear part hingedly connected to said front portion so as to be rockable relative to the front portion and a lower part connected by link means only to said upper rear part, so as to move backwards and forwards relative to said upper rear part, said link means being so constructed as to positively constrain the lower rear part to partake of a forward movement as the upper rear part rocks toward the front portion.

In order that the invention may be more readily understood a three-part last made in accordance with the invention will now be more particularly described with the aid of the accompanying drawings, wherein:

Figure 1 is a part-sectional elevation of the last in the open or "broken" position.

Figure 2 is a view of the same last in a position about midway between the open or "broken" position and the closed position.

Figure 3 is a view of the same last in the closed position, and

Figure 4 is a fragmentary plan view, to an enlarged scale, on line 4—4 of Figure 3.

In the drawings the last is shown in the position in which it could be used as a shoe tree but it will be understood that when used in the manufacture of shoes it is mounted in an inverted position on a rigid support.

The last comprises a front portion 2 constituting a forepart conforming to the toe and waist portions of the desired foot shape and a two-part rear portion 3 made up of an upper part 4 and a lower part 5 movable relatively to the upper part 4. The upper part 4 conforms to the ankle portion of the desired foot shape and the lower part 5 corresponds to the heel portion of the foot shape. The upper part 4 is provided with a transverse semi-cylindrical projection 6 which seats in a correspondingly shaped transverse recess 7 in the front portion 2 in such a manner as to permit of angular movement of the portions 3, 4 which are connected together by one or, as shown, by a pair of slotted links 8 which engage pins 9, 10 inserted in holes drilled transversely in the portions 2 and 3 respectively, the pins 9, 10 being so positioned and the links 8 being so shaped that while the projection 6 is held firmly in the recess 7 in all positions of relative movement of

the portions 2 and 3, the portions 2, 3 tend to occupy either the relative positions shown in Fig. 1 or the relative positions shown in Fig. 3. This form of connection between front and rear portions of a last is well known.

In the last of the present invention the upper ankle part 4 and lower heel part 5 of the rear portion 3 of the last are movable relatively to one another in such wise that when the rear portion 3 is moved angularly relatively to the front portion or forepart 2 from what may be regarded as the normal position of the parts shown in Fig. 3, the lower part 5 is moved forwardly relative to the upper part 4 into the position shown in Fig. 1 in which the widest portion of the rear portion 3 of the last, which is at the part of the last corresponding to the heel, is forwardly of its normal position and consequently the last can be removed from, or inserted into, a shoe without distorting or stretching the upper edge of the shoe. This result is attained in the construction shown in the drawings by providing a plane of cleavage between the parts 4, 5 in circular arcs 11, 12 extending in the closed last (see Figure 3) from a position below the hinge connection of the front and rear portions 2, 3 upwardly to and through the back of the last, and by connecting the parts 4, 5 together by a control link 13 which is provided with an arm 14, the purpose of which will be described later. The link 13 is mounted by its opposite ends on the pin 10 already referred to and on a pin 15 inserted in holes bored in suitable positions in the part 5. The radius of the circular arcs 11, 12 and the length and mounting of the link 13 are so chosen that for the small relative movement of the parts 4, 5 there is no substantial separation of the parts, or in other words, for all practical purposes, the parts 4, 5 may be considered as having a relative translatory or sliding movement.

The pin 15 to which one end of the control link 13 is pivotally attached passes transversely through a recess 16 provided in the upper forward portion of the heel part 5 and the pin 10 to which the link 13 is also pivotally attached passes transversely through an open-end slit 17 provided in the region of the projection 6 on the forward end of the ankle part 4. The arm 14 of the control link 13 extends forwardly, that is, toward the toe portion of the last, to engage an abutment provided in the cavity 18 formed in the forepart 2 of the last through which cavity 18 transversely extends the pin 9 to which one end of each of the links 8 is pivotally attached. The abutment is located at or adjacent the point of connection of the hinge links 8 to said forepart 2 and is preferably constituted, as shown, by said pin 9.

Figure 3 shows the last in its closed position, that is, the position in which it acts as a tree for the shoe in which the last has been inserted, and it will be understood from Figure 3 that the control link 13 is made of such a form that the outer end of the arm 14 thereof abuts the pin 9 in the forepart 2 of the last. In the process of opening or "breaking" the last, for the purpose of removing it from the shoe the ankle part 4 is rocked toward the forepart 2 in known manner and throughout this process, (as exemplified by position shown in Figure 2) until the open position (see Figure 1) is reached, the arm 14 of the control pin 13 bears against the pin 9 so that that pin serves as an abutment to constrain the link 13 to pivot about the hinge pin 10 in the ankle

part 4 and thus impart a positive forward movement to the heel part 5 with which said link 13 is also operatively connected by means of pin 15. The abutment of the arm 14 of the link 13 on to the pin 9 in the forepart 2 of the last serves to limit the rearward displacement of the heel part 5 as the ankle part 4 rocks toward the forepart 2. The arm 14 also positively regulates the rearward displacement of the heel part 5 during the closing of the last. The control imposed on the movement of the heel part 5 during the opening of the last ensures that the last is automatically shortened in such a manner that the shoe is not distorted or damaged.

I claim:

1. A three-part shoe last comprising a front portion and a two-part rear portion consisting of an upper rear part hingedly connected to said front portion so as to be rockable relative thereto and of a lower part connected by link means only to said upper rear part, so as to move backwards and forwards relative to said upper rear part, said link means being so constructed as to positively constrain said lower rear part to partake of a forward movement as said upper rear part rocks toward said front portion.

2. A three-part shoe last comprising a forepart, an ankle part hinged adjacent its lower front edge to said forepart, and a heel part suspended below said ankle part solely by means of a link device which cooperates with said forepart to cause said heel part to move relative to said ankle part and toward said forepart as said ankle part is hinged toward said forepart.

3. A shoe last comprising, in combination, a forepart conforming to the toe and waist portions of the desired foot shape, having toward its lower rear edge a transverse formation constituting one element of a fulcrum and provided in the region of said transverse formation with a forwardly extending cavity through which a first pin passes transversely; an ankle part having a transverse formation which is complementary to the formation of said forepart and which constitutes the other element of a fulcrum so that said ankle part can be rocked on and in relation to said forepart and having an open-end slit extending through the front portion of said ankle part in the region of its transverse formation and through which a second pin passes transversely; at least one link element engaging said first and second pins so as to hingedly interconnect said forepart and said ankle part; a heel part having a recess in the upper forward portion thereof and through which a third pin passes transversely, and a control link apertured for the reception of said second and third pins so as to swingably interconnect said ankle part and said heel part, said control link having a formation which extends into the cavity of said forepart for contacting with an abutment face therein so that when during the act of "breaking" the last the ankle part is rocked towards the forepart to which it is hingedly connected, the control link by reason of contacting the abutment face in the cavity of said forepart is caused to move the heel part forwardly in relation to the ankle part.

4. A last as claimed in claim 3, characterised in that the control link is formed with an arm which co-operates with an abutment face constituted by said first pin which passes transversely through the cavity of the forepart.
